DESIGN FOR A DRESS

Vera E. Jacobs, New York, N. Y.

Application November 13, 1940, Serial No. 96,518

Term of patent 3½ years

To all whom it may concern:

Be it known that I, Vera E. Jacobs, a citizen of the United States, residing at #1016 Fifth Avenue, New York city, in the county of New York and State of New York, have invented a new, original, and ornamental Design for a Dress, of which the following is a specification, reference being had to the accompanying drawing, forming part thereof.

Figure 1 is a front view of a dress, showing my new design; and

Figure 2 is a rear view of the same.

The characteristic feature of my design resides in the combination on the specific shirt-waist dress disclosed of the V-shaped lace yoke on the front thereof, said V-shaped yoke being bisected by the full length button panel down the front of the dress, in association with the straight matching lace yoke on the back of the dress, all as shown.

I claim:

The ornamental design for a dress, substantially as shown and described.

VERA E. JACOBS.
